US00D862457S

(12) **United States Design Patent** (10) **Patent No.:** **US D862,457 S**
(45) **Date of Patent:** ** *Oct. 8, 2019

(54) **ELECTRONIC DEVICE**

- (71) Applicant: **Samsung Electronics Co., Ltd.**, Suwon-si (KR)
- (72) Inventors: **Sungkwon Kim**, Seoul (KR); **Kwanue Hong**, Yongin-si (KR); **Jeisung Park**, Gwacheon-si (KR); **Seo Lee**, Yongin-si (KR); **Seungchan Lee**, Seoul (KR); **Yonghee Cho**, Seoul (KR)
- (73) Assignee: **Samsung Electronics Co., Ltd.**, Suwon-si (KR)
- (*) Notice: This patent is subject to a terminal disclaimer.

(**) Term: **15 Years**

(21) Appl. No.: **29/648,784**

(22) Filed: **May 24, 2018**

Related U.S. Application Data

- (63) Continuation-in-part of application No. 29/618,420, filed on Sep. 21, 2017, now Pat. No. Des. 820,834, (Continued)

(57) **CLAIM**

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines shown in the drawings depict portions of the electronic device that form no part of the claimed design.

1 Claim, 5 Drawing Sheets

Related U.S. Application Data

which is a continuation of application No. 29/595, 927, filed on Mar. 3, 2017, now Pat. No. Des. 821, 390, which is a continuation of application No. 29/588,292, filed on Dec. 20, 2016, now Pat. No. Des. 821,389.
